Attorney

UNITED STATES PATENT OFFICE.

FRANS EMILE KARTHAUS AND CORNELIS JOSEPH HOOGVELD, OF DELFT, NETHERLANDS.

CRANK CHAMBER.

Application filed July 29, 1921. Serial No. 483,870.

To all whom it may concern:

Be it known that we, FRANS EMILE KAR-
THAUS and CORNELIS JOSEPH HOOGVELD, sub-
jects of the Queen of the Netherlands, re-
siding at Delft, Simonstraat 105, Neth-
erlands, have invented certain new and use-
ful Improvements in Crank Chambers, of
which the following is a specification.

This invention relates to a device for di-
viding or closing a crankchamber, more es-
pecially if this dividing or closing has to be
carried out at the place where an excentric
part of the crankshaft is situated.

The invention presents special advantages
if applied for the purpose of separating
parts of the crankchamber of a two-stroke-
cycle internal combustion engine, said parts
belonging to different cylinders of a multi-
ple cylinder engine of the style where the
crankchamber serves the purpose of a scav-
engaging pump.

These engines presented the defect that,
in case the respective pistons of the respec-
tive cylinders did not occupy the same posi-
tion, the crankchamber would be divided in
as many pumping chambers, separated from
each other, such being the case if the cylin-
ders were placed in a radial row about the
crankshaft.

Up to now, fixed partitions have been in-
serted, involving the necessity of providing
the crankshaft with as many two-throw
cranks as there are pumping chambers.

This construction of the engine, not only
causes complication and high cost but also an
increase in dead weight and at the same time
also a considerable increase in size in the
crankshaft. This invention avoids these
difficulties because it allows of having a
closing or dividing wall at the place of an
excentric part of the crankshaft. Accord-
ing to the invention this has been realized
by means of one or more discs, concentric
with the shaft and running in a correspond-
ing groove in the inner wall of the crank-
chamber, said discs being provided with an
opening for the passage of the excentric
part of the crankshaft.

In order to have a tight joint between
these discs and the crankchamber they may
be made so thin that the difference in pres-
sure at each side will cause them to have
their circumferential part lie tight against
a side of the groove in the crankchamber.
This is of special importance if the disc,

at the place where the crankshaft passes 55
through, is fixed to this latter.

In case of an engine construction that has
been rendered a practical possibility in con-
sequence of the invention, viz, that whereby
the connecting rods of two pistons of two 60
opposite cylinders engage one and the same
crankpin, the disc has been keyed to the
crankpin with the aid of two flanged sleeves,
these latter as well serving the purpose of
procuring running guides for the connect- 65
ing rod heads.

In the accompanying drawing the inven-
tion has been further explained by means of
a section of a two cylinder engine, with the
cylinders in opposition. 70

The cylinders 1 and 2 are mounted upon
the two-part crankchamber 3 in the usual
manner with the aid of flanges. The crank-
shaft is built up of two shaft ends 4 and 5,
each provided with a flywheel, indicated as 75
6 and 7 and connected by one and the same
crankpin 8.

One end of this crankpin and both of the
shaft ends 4 and 5 are joined to said fly-
wheels by means of a conical end and a key 80
while the other end of said crankpin fits
with a cylindrical end into one of the fly-
wheels. Both of the pistons 9 and 10 are
connected to the crankpin by means of con-
necting rods 11 and 12.

Between the connecting rods, a disc 13 is 85
mounted, serving as a partition and having
an opening for the passage of the crankpin.
The circumferential part of said disc runs
in a groove, formed by recesses in two rings
14 and 15, these rings serving the purpose 90
of centering both parts of the crankchamber.

The disc 13 is mounted rigidly on the
crankpin by means of two flanged sleeves 16
and 17 riveted to the disc and keyed to the
crankpin with the same key 18 as is used to
key the flywheels 7 and 8 thereto. These 95
flanged sleeves procure a running guide for
the heads of the connecting rods 11 and 12.

It may be remarked that the invention
also gives a favourable distribution of tan-
gential pressure upon the crank, because,
e. g., the construction as given in the draw-
ing, allows of a live stroke at each half turn. 100

Any kind of engine may be fitted with a
device for dividing the crankchamber into 105
separate parts in the manner disclosed by
the invention, if such be desired.

Furthermore it is possible to replace one

or both of the side walls of the crankchamber of some engine, by a disc, according to the invention, so that a rotating crankpin extends from the crankchamber.

Having now described our invention, what we claim as new and desire to secure by Letters Patent is:—

1. Means for the purpose described, comprising a crank chamber, a crankshaft therein having an eccentric portion, a thin flexible disc separating the chamber into two portions, said disc being keyed to said eccentric portion by means of two opposing flanged sleeves, the sleeves affording guide surfaces for heads of connecting rod.

2. Means for the purpose described, comprising a crank chamber, a crankshaft therein, a disc within the chamber and connected to the crankshaft by means of two flanged sleeves riveted to the disc, said sleeves being keyed to the crankshaft.

3. A device according to claim 1, said disc

having an eccentric aperture, said eccentric portion of the crank shaft being received in the eccentric aperture.

4. A device according to claim 2, said disc having an eccentric aperture, said crank shaft having an eccentric portion received in said aperture, headed connecting rods entering the chamber, said flanged sleeves affording guide surfaces for the heads of the connecting rods.

5. Means according to claim 1, said disk being connected to the crank shaft at but one point.

6. Means according to claim 1, said disk being connected to the crank shaft intermediate the ends of the said eccentric portion of the crank shaft.

In testimony whereof we affix our signatures.

C. J. HOOGVELD.
F. E. KARTHAUS.
